ILLUMINATED CANE

George Dyer, Cheyenne, Wyo.

Application July 9, 1938, Serial No. 218,416

5 Claims. (Cl. 240—6.42)

The invention aims to provide a new and improved illuminated cane which may be effectively used to light the user's way at night.

With the foregoing in view, the invention resides in the novel subject matter hereinafter described and claimed, the description being accomplished by reference to the accompanying drawing.

Fig. 1 is a side elevation of a cane constructed in accordance with the invention.

Fig. 2 is an enlarged fragmentary vertical sectional view.

Fig. 3 is a horizontal sectional view on line 3—3 of Fig. 2.

Fig. 4 is a detail horizontal section through one of the lens-carrying frames with the lens omitted.

A preferred construction has been illustrated and will be rather specifically described, with the understanding, however, that variations may be made within the scope of the invention as claimed.

The cane is formed from upper and lower sections U and L respectively, of wood, light metal alloy or any desired composition, and while a cane has been shown with a curved handle H, it is to be understood that the invention may be embodied in a cane having merely a knob.

Threaded collars 5 and 6 are secured respectively to the sections U and L and are interengaged with each other to hold said sections connected, the collar 6 being preferably so finished as to constitute an attractive band or ferrule. The upper section U is formed with a central vertical recess 8 and the lower section L is provided with a similar recess 7, the two recesses being in communication to enclose a bulb 9 and a battery 10, said upper section being equipped with a plurality of circumferentially spaced lenses 11 for the emission of light rays from said bulb 9.

The lenses 11 are held by rectangular metal frames 12 fitting snugly into circumferentially spaced openings 13 which extend from the exterior to the interior of the upper cane section U, each opening 13 being provided with flat vertical side walls against which the side walls 14 of the frame 12 abut. The outer edges of these side walls 14 are bent to provide inwardly projecting flanges 15 abutting the lens 11, and outwardly projecting flanges 16 abutting the outer side of the section U. The inner edges of the walls 14 are bent to provide hooked flanges 17 extending longitudinally thereof. While these flanges 17 project outwardly somewhat from the

walls 14, they do not interfere with inward insertion of the various frames into the openings 13, for the upper and lower end members 18 of each frame are of less width than the side walls 14, leaving the inner portions of the latter free 5 to spring inwardly toward each other as the frames are being inserted into the openings.

Reflectors 19 formed from sheet metal plates are disposed at the wall of the recess 8 between the frames 12, said reflectors having vertical 10 edges provided with hooked flanges 20 which engage the hooked flanges 17 of said frames, the reflectors and frames being thus effectively tied together. If desired, the lower end of each reflector 19 may be provided with a lug 21 to aid 15 in sliding it into place and to permit removal for polishing if desired. Filler strips 22 of paper or the like may be employed between the reflectors 19 and the wall of the recess 8.

The lenses 18 abut the flanges 15 and are secured in place by upwardly bent lugs 23 integral with the inner edges of the frame end members 18.

A metal sleeve 24 is received partially in the recess 7 and partially in the recess 8, the upper 25 end of said sleeve being provided with an integral inwardly projecting flange 25 to which a metal socket 26 is suitably secured, said socket being open at both its upper and lower ends to receive the threaded shell 27 of the bulb 9. The usual 30 central contact 28 of the bulb contacts with the central terminal 29 of the battery 10 and the latter is held upwardly by means of the conventional coil spring 30 which is in electrical contact with the lower end of said battery, whether the 35 latter consist of one cell or several cells. A suitable conductor 31 is carried by the lower section L and is electrically connected at 32 with the spring 30, the upper end of said conductor being electrically connected at 33 with the collar 6. 40 Another conductor 34 is carried by the upper section U and is electrically connected at 35 with the collar 5, said conductor 34 extending into a suitable switch casing 36 and being cooperable with a movable switch member 37, said switch 45 member having a finger-actuated control member 38. Also extending into the casing 36 for coaction with the switch member 37, is a conductor 39, the lower end of which projects inwardly from the wall of the bore 8 as shown 50 at 40 and constitutes a fixed contact which abuts the upper side of the flange 25, limiting the upward movement of the sleeve 24 as well as constituting part of the current-conducting means for the bulb 9.

When the switch member 37 bridges the normal gap between the two conductors 34 and 38, current flows from the terminal 29 of the battery 10 through the central contact 28 of the bulb 9, through the filament of this bulb to the shell 27 thereof, from this shell through the socket 26, flange 25, contact 40 and conductor 38 to the switch member 37, through the conductor 34, and the collars 5 and 6 to the conductor 31, and from this conductor back to the battery through the spring 30, thereby effecting illumination of said bulb 9. Rays are emitted from this bulb through the lenses 11 and the light is, of course, intensified by the reflectors 19. When the finger-piece 38 is operated to move the switch member 37 to switch-open position, the current for the bulb is, of course, broken.

Whenever it is necessary to install a new bulb or a new battery, the two sections U and L may be readily separated by unscrewing the threaded connection between the collars 5 and 6, whereupon the sleeve 24, socket 26 and bulb may be removed from the upper section and the battery 10 may be removed from the lower section.

It will be seen from the foregoing that novel and advantageous provision has been made for carrying out the objects of the invention, and while preferred details have been shown, variations may be made within the scope of the invention as claimed.

I claim:

1. An illuminated cane having a central vertical recess and circumferentially spaced openings from its exterior to said recess, said openings having vertical side walls, lens-carrying frames fitting within said openings and having side walls lying against said side walls of said openings, the inner edges of said frame side walls being provided with hooked flanges extending longitudinally thereof, vertical reflectors at the side wall of said recess between said openings, said reflectors having vertical edges provided with hooked flanges engaged with the aforesaid hooked flanges of said frame side walls, means for mounting a bulb in said recess, and current-conducting means for said bulb.

2. A structure as specified in claim 1, said frames having upper and lower end members of less width than said frame side walls leaving the flanged inner edge portions of the latter free to

spring inwardly toward each other when inserting the frames from the exterior of the cane.

3. An illuminated cane comprising upper and lower sections and means detachably connecting the same, said sections being provided with central vertical communicating recesses, said upper section being provided with a lens for the emission of light from its recess, a sleeve upwardly inserted into said recess of said upper section, the upper end of said sleeve being provided with an inwardly projecting metal flange, a metal bulb socket secured to the inner edge of said flange and open at both its upper and lower ends, a bulb threaded downwardly through said socket, a battery in the recess of the lower cane section, a spring under and contacting with said battery to hold the latter upwardly against the usual central contact of said bulb, and current-conducting means for said bulb including a fixed contact projecting inwardly from said upper section and abutting the upper side of the aforesaid flange.

4. An illuminated cane having a central vertical bulb-containing recess, said cane having circumferentially spaced openings from its exterior to said recess, lens-carrying frames in said openings, tie members disposed at the wall of said recess between said openings, and means connecting said frames with said tie members and thereby holding said frames against outward movement from said openings.

5. An illuminated cane having a central vertical recess and circumferentially spaced openings from its exterior to said recess, said openings having vertical side walls, lens-carrying frames fitting within said openings and having side walls lying against said side walls of said openings, the inner edges of said frame side walls being provided with hooked flanges extending longitudinally thereof, vertical plates at the side wall of said recess between said openings, said plates having vertical edges provided with hooked flanges engaged with the aforesaid hooked flanges of said frame side walls, means for mounting a bulb in said recess, and current-conducting means for said bulb.
